UNITED STATES PATENT OFFICE.

HENRY JOSEPH GRENIER, OF BRIDGEPORT, CONNECTICUT.

SUGAR-DISPENSING DEVICE.

1,312,320.

Specification of Letters Patent.

Patented Aug. 5, 1919.

Application filed May 16, 1919. Serial No. 297,518.

To all whom it may concern:

Be it known that I, HENRY J. GRENIER, a citizen of the United States, and a resident of Bridgeport, in the county of Fairfield and State of Connecticut, have invented a new and Improved Sugar-Dispensing Device, of which the following is a full, clear, and exact description.

This invention relates to new and useful improvements in sugar bowls, and pertains more particularly to a device of this character in which a predetermined quantity of sugar may be discharged from the bowl.

The invention contemplates a sugar-bowl or receptacle in which the sugar is contained within a closed receptacle for the purpose of maintaining it in a clean and sanitary condition.

A further object of the invention is to provide a sugar bowl in which a predetermined quantity of sugar may be obtained without exposing the bulk of the sugar in the receptacle.

With the above and other objects in view, reference is had to the accompanying drawings in which—

Figure 1 is a view partly in elevation and partly in section;

Fig. 2 is a top plan view of the supporting base with the receptacle removed.

Referring more particularly to the drawings, the reference character 5 designates the sugar receptacle, which is provided near its open end with a set of screw threads 6. Having threaded engagement with the screw threads 6, is a flange 7, which is an integral part of a downwardly projecting tubular member 8, and rigidly secured, as at 9, to the outer walls of said tubular member 8 and in spaced relation, are supporting legs 10.

Secured to the upper part of the tubular member 8 on its interior, and at the base of the threaded flange 9, is a plate 11. The plate 11 is provided centrally of its body portion with a circular opening in which is secured a pipe or spout 12. Rotatably mounted in the plate 11, at a point adjacent the spout 12, is a plate 13, which plate is rigidly carried by means of a vertically extending standard 14, the lower end of which extends below said plate 11. The rotatable plate 13 is adapted to normally lie in a position substantially clear of the opening to the spout 12, but under certain conditions the plate 13 is adapted to move to a posi-

tion where it will close the spout 12, as shown in dotted lines in Fig. 1.

Mounted on the lower end of the standard 14, is a crank arm 15, and connected to said crank arm 15, is a flexible member 16, the other end of which is connected as at 17, to a reciprocating lever 18, the free end of the lever being provided with an operating button 19. Intermediate its points of connection with the crank arm 15 and with the operating lever 18, the flexible member 16 passes over a pulley 20, as more clearly shown in Fig. 1. Interposed between the crank arm 15 and the side of the tubular member 18, is a coil spring 21, the purpose of which will be hereinafter more fully set forth.

Pivoted secured as at 22, to the lower end of the spout 12, is a plate 23, and projecting from one side of the plate 23 is a pin 24, which is adapted to engage in a slot 25 in the lower end of the reciprocating lever 18. Secured to the pin 24 at one of its ends and to the under side of the plate 23 at the other end, is a coil spring 26.

Having thus described the invention, the operation thereof is as follows: The receptacle 5 is filled with sugar, after which the tubular member 8 is screwed to place thereon. With the parts in the position shown in Fig. 1, which is their normal position, the sugar flows from the receptacle 5 and fills the discharge spout 12. If now the reciprocating lever 18 be depressed by the thumb of the hand which grasps the handle 27, it will be seen that the plate 23 will be rocked about its pivot 22, to open the lower end of the discharge spout 12, and permit of a free flow of the sugar contained in said discharge spout therefrom.

Simultaneously with the opening of the plate 23, the plate 13 will be rocked to the position shown in dotted lines in Fig. 1, where it will close the entrance to the discharge spout 23, thus preventing the contents of the receptacle 5 from escaping into the spout 12 and through the tubular member 8.

After the sugar has all passed from the spout 12, if the operating button 19 be released, the springs 21 and 26 serve to return the parts to their normal position, which opens the upper end of the spout 12 and permits said spout to be again filled with sugar, the same being retained therein by the closed position of the plate 23.

The elongated slot 25 permits of a movement of the reciprocating lever 18 relative to the plate 23, before said plate is rocked about its pivot, this last-mentioned operation not taking place until the pin 24 reaches the extreme inner end of the elongated slot 25. This movement of the reciprocating lever 18 will be sufficient to move the plate 13 to the position where it 10 closes the entrance to the spout 12 prior to the opening of the lower or discharge end of said spout.

Having thus described the invention, what is claimed as new is—

15 1. A device of the character described comprising a base, a receptacle movably secured to said base, a horizontal partition carried by said base, a spout carried by said partition, a hinged closure for the lower end 20 of said spout, a sliding closure for the upper

end of said spout, and means comprising a slotted plunger and a flexible connection for simultaneously operating said hinged closure and said sliding closure.

2. A device of the character described comprising a base, a horizontal partition carried by said base, a receptacle carried by said base, a spout carried by said horizontal partition and adapted to communicate with said receptacle, a hinged closure for the lower end of said spout, a sliding closure for the upper end of said spout, a slotted plunger connected to said hinged closure and adapted for moving the same to open position, and a flexible connection between 30 said slotted plunger and said sliding closure for operating the latter upon operation of the hinged closure.

HENRY JOSEPH GRENIER.
